Primary Examiner — David Muller

(74) Attorney, Agent, or Firm — Bryce D. Miracle;
Miracle IP(57) CLAIM

The ornamental design for a gastric feeding tube cover, substantially as shown and described.

DESCRIPTION

FIG. 1 is a front perspective view of the gastric feeding tube cover showing the new design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The rear side of the gastric feeding tube cover not shown forms no part of the claimed design.
